Primary Examiner—M. N. Pandozzi

(57) **CLAIM**

The ornamental design for a micro computer thermal mug, as shown and described.

DESCRIPTION

FIG. 1 is a front view showing my new design.

FIG. 2 is a rear view thereof.

FIG. 3 is a left end view thereof.

FIG. 4 is a right end view thereof.

FIG. 5 is a top view thereof.

FIG. 6 is a bottom view thereof.

FIG. 7 is a perspective view thereof; and,

FIG. 8 is another perspective view thereof.

The surface(s) or portion(s) of the article not shown in the drawing or described in the specification form(s) no part of the claimed design.

UNITED STATES PATENT AND TRADEMARK OFFICE
CERTIFICATE OF CORRECTION

PATENT NO. : Des. 494,010 S
DATED : August 10, 2004
INVENTOR(S) : Yuen, Se Kit

Page 1 of 1

It is certified that error appears in the above-identified patent and that said Letters Patent is hereby corrected as shown below:

Title page.

Item [76], Inventors, should read -- **Yuen, Se Kit.** --

Signed and Sealed this

Twenty-fourth Day of May, 2005

A handwritten signature in black ink, appearing to read "Jon W. Dudas". The signature is written in a cursive style with a large, stylized "J" and "W".
